UNITED STATES PATENT OFFICE.

LOUIS CONRAD MEYEROTT, OF EVANSVILLE, ILLINOIS.

DUST-COLLECTOR.

SPECIFICATION forming part of Letters Patent No. 654,997, dated July 31, 1900.

Application filed February 23, 1900. Serial No. 8,243. (No model.

To all whom it may concern:

Be it known that I, LOUIS CONRAD MEYEROTT, a citizen of the United States, and a resident of Evansville, in the county of Randolph 5 and State of Illinois, have invented a new and Improved Dust-Collector, of which the following is a full, clear, and exact description.

The object of the invention is to provide a new and improved dust-collector more especially designed for use in flour-mills and arranged to provide a large dust-collecting surface and to insure a constant cleaning of the filtering-cloth and removal of the dust from the dust-filtering compartments without danger of dust-laden air passing into the compartments during the discharge of the dust into the conveyer.

The invention consists of novel features and parts and combinations of the same, as will be 20 fully described hereinafter and then pointed out in the claims.

A practical embodiment of the invention is represented in the accompanying drawings, forming a part of this specification, in which 25 similar characters of reference indicate corresponding parts in all the views.

Figure 1 is a longitudinal sectional elevation of the improvement on the line 1 1 in Fig. 2. Fig. 2 is a transverse section of the 30 same on the line 2 2 in Fig. 1, and Fig. 3 is an end elevation of the same.

The improved dust-collector is mounted on a suitably-constructed frame A, in the lower portion of which are journaled longitudinally-extending shafts B, carrying sets of rollers B' B² for supporting the heads C' C² of a drum C, adapted to rotate when the shafts B of the rollers B' B² are turned to cause the drum to 35 rotate in the direction of the arrow a'. On the drum C, between the heads C' C², are arranged a plurality of longitudinally-extending filtering-cloth compartments D, arranged to gradually collapse and to suddenly expand, as hereinafter more fully described, for the 40 removal of the dust carried by the dust-laden air which passes into the drum C through a dust-flue E. Each of the filtering-cloth compartments D is provided with a shell of filtering-cloth D', each shell being open at the inner end, strips D², of wood or other material, securing the cloth to the drum around a longitudinally-extending opening C³, formed in

the peripheral surface of the drum C to establish communication between the interior of the drum and the interior of the compartment. The cloth is stretched at its ends over transversely-extending bars D³, connected with each other by longitudinal rods D⁴, and each of said bars D³ is provided with a longitudinal bar D⁵, extending outwardly through the end of the cloth to pass through radial slots C⁴, formed in the heads C' C² of the drum C. The bars D⁵ are pressed outward by springs F, coiled around rods F', held in recesses formed in the heads C' C², so that the cloth of the compartments is normally held in a stretched position over the bars D³ until the bars D⁵ are pushed inward against the tension of the springs F by fixed cams G, secured on the frame A at the ends thereof, as 70 will be readily understood by reference to Fig. 3. When the drum C rotates in the direction of the arrow a', then the bars D⁵, when nearing an uppermost position, come in contact with the cams G, and are thus pressed inward in the radial slots C⁴ to cause the bars D³ to move in a like direction, so that the cloth D' becomes slack, and consequently the compartment D, while moving into an uppermost position, collapses until the bars D⁵ suddenly 75 drop off the cams G, and the springs F now force the bars D⁵ outward to again cause the bars D³ to stretch the cloth, and thereby jerk the same and cause the adhering dust to become loose and drop inside of the compartment through the opening C³ down into a conveyer H of any approved construction and extending longitudinally through the drum C. The conveyer H, as shown, is provided with a conveyer-casing H', supported at the 80 ends on screw-rods H², adjustably held on the main frame, and one end of said casing H is provided with a discharge-spout I for carrying off the dust moved to the entrance of the spout by the conveyer-screw H³, extending in 85 the casing H' and secured on a shaft H⁴, journaled in the ends of the casing. One end of the shaft H⁴ carries a pulley H⁵, over which passes a belt J, also passing over pulleys B³ on the shafts B. The other end of the shaft H⁴ carries a pulley H⁶, connected by belt with 90 other machinery for imparting a rotary motion to the shaft H⁴ and the conveyer-screw H³, and the rotary motion of the shaft is 95 100

transmitted by the pulleys H⁵ and B³ and the belt J to the shafts B, so that the rollers B' B² thereof rotate the drum C in the direction of the arrow a', as previously mentioned.

- 5 In order to prevent dust-laden air from passing from the drum C into a compartment D at the time the latter is collapsing, it is necessary to provide the inside of the drum C with longitudinally - extending spaced 10 brushes K, adapted to engage the segmental top H⁷ of the conveyer-casing (see Fig. 2) at the time the brushes pass into an uppermost position. The brushes are spaced on opposite sides of an opening C³, so that when a compartment D passes into an uppermost position then the corresponding set of brushes K is in contact with the top H⁷, and consequently the interior of the drum is cut off at this point from the interior of the compartment 20 to prevent dust-laden air from passing into the compartment during the time the drum collapses and is again suddenly expanded, as previously explained.

As the conveyer extends eccentrically 25 through the drum C, it is necessary to pack the ends of the heads C' C² on the ends A' of the casing, and for this purpose suitable packing-rings L are employed, as plainly indicated in Fig. 1. The upper portions of the ends A' 30 are preferably removable, so as to permit of obtaining convenient access to the interior of the drum for examining and repairing the brushes or other parts of the device.

From the foregoing it is evident that when 35 the machine is in operation the dust-laden air passing into the drum C can readily pass through the openings C³ into the several expanded filtering-cloth compartments D, so that the dust carried by the air is retained by 40 the filtering-cloth D', while the air passes through the pores of the cloth to the outside of the compartments into the room in which the device is located. As the drum C revolves the compartments D are carried upward to 45 be finally cut off at the openings C³ from the interior of the drum by the adjacent brushes K, passing upon the top H⁷ of the conveyer-casing H'. During this movement into a final uppermost position the compartments are 50 collapsed by the bars D⁵ engaging the cams G, as previously explained, and are finally quickly expanded by the action of the springs F, so that the dust adhering to the inside of the cloth is jerked off the frame and drops 55 down through the openings C³ into the conveyer-casing H', to be moved longitudinally therein by the conveyer-screw H³ to the spout I, which carries the dust to one side of the machine.

60 The machine is simple and durable in construction, is not liable to get out of order, and insures a constant cleaning of the cloth and a removal of the dust from the dust-gathering compartments, as above explained.

65 Having thus fully described my invention, I claim as new and desire to secure by Letters Patent—

1. A dust-collector, comprising a revoluble drum having slotted and recessed heads and longitudinal openings in its periphery between the heads, a plurality of filtering-cloth compartments secured with their inner, open ends on the peripheral surface of said drum, the openings of a compartment leading to an opening in said periphery, stretching-bars for the cloth of a compartment, and having extensions mounted to slide in the radial slots in the heads of the drum, springs in the recesses of the heads of the drum and pressing on said extensions to force them outward, and fixed cams adapted to engage the said extensions, to move the latter gradually inward against the tension of said springs and collapse the compartment, as set forth. 70

2. In a dust-collector, the combination with a drum having longitudinal openings and provided with recessed and slotted heads, said heads being of greater diameter than the body of the drum, of a plurality of filtering-cloth compartments arranged on the periphery of the drum, each compartment extending longitudinally of the drum over an opening thereof, bars projecting from opposite ends of the compartments and working in the slots of the heads of the drum, rods secured in the recesses of the heads and projecting through the bars, springs on said rods and bearing against the bars of the compartments, and fixed cams engaging the ends of the bars projecting through the heads, as the drum is revolved, as and for the purpose set forth. 90

3. A dust-collector, comprising a drum having longitudinal openings and provided with heads of greater diameter than the body of the drum, said heads being slotted and recessed, a plurality of filtering-cloth compartments arranged on the peripheral surface of the drum, each compartment extending longitudinally of the drum over an opening thereof, rods projecting from the ends of the compartments and extending through the slots of the heads, springs arranged in the recesses of the heads and forcing the rods outward, fixed cams for engaging the ends of the rods, a conveyer-casing in the drum and having an opening in its top, a screw conveyer in said casing, and brushes between the top of the conveyer-casing and the drum, substantially as herein shown and described. 105

4. A dust-collector, comprising a drum having longitudinal openings and provided with heads of greater diameter than the body of the drum, said heads being slotted and recessed, a plurality of filtering-cloth compartments arranged on the periphery of the drum, each compartment extending longitudinally of the drum over an opening thereof, stretcher-bars arranged transversely at the ends of the compartments and connected by rods with each other, bars projecting from the stretcher-bars beyond the ends of the compartments and extending through the slots of the drum-heads, springs in the recesses of the drum- 110 115 120 125 130 135

heads and pressing said bars outward, a conveyer-casing in the drum and having an opening in its top, a screw conveyer in the casing, and brushes secured to the inner face of
5 the drum, one at each side of each opening thereof, substantially as herein shown and described.

In testimony whereof I have signed my name to this specification in the presence of two subscribing witnesses.

LOUIS CONRAD MEYEROTT.
